COMBINED MEAT SERVER AND HOLDER RACK

Paul Young, Washington, D.C.

Application March 20, 1959, Serial No. 55,086

Term of patent 14 years

(Cl. D44—29)

Figure 1 is an exploded view in side elevation of a combined meat server and holder rack, showing my new design, the wire rack member being shown in raised position;

Figure 2 is a top plan view thereof with the wire rack in place;

Figure 3 is a sectional view on the line 3—3 of Figure 2;

Figure 4 is a sectional view on line 4—4 of Figure 1;

Figure 5 is a sectional view on line 5—5 of Figure 1;

Figure 6 is a sectional view on line 6—6 of Figure 1.

The characteristic features of my invention are shown in the drawing in full lines.

I claim:

The ornamental design for a combined meat server and holder rack, as shown and described.
